UNITED STATES PATENT OFFICE

121,119

DESIGN FOR A CENTERPIECE BOWL OR SIMILAR ARTICLE

Rowena Reed Kostellow, Pittsburgh, Pa., assignor to United States Glass Company, Pittsburgh,
Pa., a corporation of Pennsylvania

Application February 5, 1938, Serial No. 74,897

Term of patent 3½ years

To all whom it may concern:

Be it known that I, Rowena Reed Kostellow, a citizen of the United States, residing at Pittsburgh, county of Allegheny, in the State of Pennsylvania, have invented a new, original, and ornamental Design for a Centerpiece Bowl or Similar Article, of which the following is a specification, reference being had to the accompanying drawing, forming a part thereof, in which—

The figure is a perspective view of a centerpiece bowl or similar article, showing my design.

The bowl is of circular contour.

The dominant feature of the design resides in the handle portions in association with the top rim and side portions of the bowl as shown.

I claim:

The ornamental design for a centerpiece bowl or similar article, substantially as shown and described.

ROWENA REED KOSTELLOW.
